UNITED STATES PATENT OFFICE.

SAMUEL A. NEIDICH, OF PHILADELPHIA, PENNSYLVANIA.

BRAIDING-MACHINE.

No. 893,810.

Specification of Letters Patent.

Patented July 21, 1908.

Application filed May 13, 1901. Serial No. 59,923.

To all whom it may concern:

Be it known that I, SAMUEL A. NEIDICH, of Philadelphia, in the State of Pennsylvania, have invented certain new and useful Improvements in Braiding-Machines, whereof the following is a specification, reference being had to the accompanying drawings.

My invention relates to machines comprising two series of thread bobbins and means to progress them in relatively opposite directions to form a plaited tube with the threads drawn from said bobbins; the plaiting operation aforesaid being effected by transposition of the threads of one series of bobbins 15 with respect to the bobbins of the other series.

In ordinary machines of the class specified, the aforesaid transposition of the threads, which occurs a number of times in each cycle 20 of relative progression of the two series of bobbins, occasions a slackening of the threads; and, in order to preserve the proper tension upon the slackened threads, such machines necessarily comprise compensating devices auxiliary to the bobbin actuating mechanism, but operated in consonance therewith, to alternately take up the threads when slackened and to relieve them when tightened.

It is the object of my present improvements to provide a machine of the class described, which is so constructed and arranged that the threads are not slackened at any period of the operation of the machine, 35 but are maintained at constant length by thread guides of novel construction; so that the auxiliary take up devices aforesaid are dispensed with, and the operation of the machine correspondingly facilitated.

Although my improvements, hereinafter described, are particularly adapted for a machine used in covering electrical conductors, it is to be understood that I do not desire to limit my claims accordingly.

My invention consists in the novel features of construction and arrangement hereinafter more definitely specified and claimed.

In the accompanying drawings, Figure I, is a top plan view of a machine conveniently embodying my invention. Fig. II, is a sectional view taken on the line II-II in Fig. I. Fig. III, is a fragmentary side elevation of a portion of the machine shown in Figs. I and II. Fig. IV, is a top plan view of one of the upper series of bobbin carriers. Fig. V, is a fragmentary sectional view showing the ar-

rangement of the upper bobbin carriers with respect to the frame which progresses them. Fig. VI, is a detailed view of one of my improved oscillatory thread guides. Fig. VII, 60 is a sectional view of one of the thread guide rock shafts.

In said figures, 1 is a stationary frame upon which are fixed the overhanging brackets 2 and 3; the former being provided with the tube 4, through which the braid is discharged. The bobbin drum 5, is mounted for rotation in said bracket 3, and is provided with a series of resilient bobbin holders 6, arranged to carry the lower series of 70 bobbins 7, whose spindles 8, are removably seated in said drum 5, and in said holders; as shown in Fig. II. Said bobbins 7, are provided with threads 9, arranged to be withdrawn under tension due to pressure of the 75 holders 6, on the spindles 8.

The upper series of bobbins 10, provided with threads 11, are mounted upon the spindles 12, which are respectively fixed in the independent bobbin carriers 13. The threads 80 11, are arranged to be withdrawn under tension due to pressure of the bifurcated upper extremities of said spindles 12, within the bobbins 10. Said carriers 13, are mounted to slide upon the track 14, upon which they 85 are retained by screws whose lower ends are entered in an annular groove in said track as indicated in Fig. II. Said track is fixed within the drum 5, and said carriers are progressed circumferentially upon said track in 90 equi-distant relation, by respective pairs of driving pins 15, which are mounted for independent reciprocation in the carrier frame 16, and normally upheld in engagement with their respective carriers 13, by the cams 17, 95 fixed in the drum 5; however, said pins are successively lowered, by the springs surrounding them, when intermediate of said cams 17, so as to permit the passage of the threads 9, between said carriers 13, and the 100 frame 16, over the lowered pins at the proper intervals in the braiding operation, the arrangement being such however, that each of said carriers is at all times engaged with at least one of its driving pins 15. It is to 105 be noted that the independent arrangement of said pins 15, is such that they may be made of minimum weight to perform the function specified. The tubular shaft 18, of said drum 5, is journaled in the bracket 3, 110 and provided at its lower extremity with the bevel gear 19, in engagement with the bevel

gear 20, upon the main driving shaft 21. The tubular shaft 22, of the frame 16, which is journaled within the shaft 18, and journaled in the frame 1, is also provided at its lower extremity with the bevel gear 23, engaged with said bevel gear 20, upon the main driving shaft 21. Said shaft 21, being provided with a tight pulley 25, and loose pulley 26, it is to be understood that the arrangement of the parts above described is such that when said shaft 21, is rotated, the drum 5, and frame 16, are rotated in relatively opposite directions, and, of course, oppositely progress the lower series of bobbins 7, and upper series of bobbins 10.

The drum 5, is provided with a peripheral flange 24, upon which are mounted the rock shafts 28, which are tubular as shown in Fig. VII, and provided with conically threaded clamp nuts 29, arranged to removably retain the thread guides or needles 30. Each of said needles consists of a bar of U shaped cross-section, whose opposite ends are eccentric, or off-set, as shown in detail in Fig. VI; and, each of said needles comprises a thread eye 31, in its shank adjoining its supporting shaft 28, and a thread eye 32, in its free extremity; both of said eyes being in communication with the thread channel 33, which exists from end to end of the needle.

The threads 9, are withdrawn from the bobbins 7, through the respective guides 34, and between the disks 35, which latter are compressed by the springs 36 to secure the proper tension upon said threads. Said threads 9, pass from the disks 35, through the eyes 31, of the needles along the channels 33, and are drawn from the eyes 32, to the discharge tube 4. The threads 11, are withdrawn from the bobbins 10, between the opposed disks 37, to the discharge tube 4, and, said disks are compressed by the springs 38, to secure the proper tension upon said threads.

The bobbins 10, are caused to carry the threads 11, alternately above and below the threads 9, extending from the bobbins 7, as follows: Each of said needle shafts 28, is provided with a crank lever 39, connected by a link 40, with an eccentric stud 41, upon a cam or wrist-plate 42. Said wrist-plates 42, are respectively fixed upon the outer extremities of the radially disposed shafts 43, which shafts are journaled in the drum 5, and respectively provided at their inner extremities with bevel gears 44, engaged with the stationary circular rack 45, which is fixed upon the frame bracket 3.

The arrangement above described is such, that during the rotation of the drum 5, each of the needles 30, is oscillated from the position shown in full lines in Fig. III, to the position shown in dotted lines in said figure, in such predetermined relation to the progression of the bobbins 10, that the threads 9, carried by the needles 30, are delivered alter-

nately above and below said bobbins 10, and the threads extending therefrom, during the continued progression of the two series of bobbins in opposite directions, and, consequently the threads 9, and 11, are braided in a tube 46, at the lower edge of the discharge tube, which is concentric with the common axis of rotation of the drum 5, and frame 16. Said tube 46, may be discharged through the tube 4, alone, or, as the covering for a central core 47, which is fed vertically upward through the hollow shaft 22, of the frame 16, as shown in Fig. II.

The needle rock shafts 28, being radially disposed with respect to the common axis of rotation of the drum 5, and carrier 16, the respective axes of oscillation of the needles 30, are, of course, radial with respect to said axis of rotation and the coincident braiding point; so that, regardless of the position of oscillation of said needles 30, the length of the threads 9, extending from the needle eyes 31, to the braiding point, and, the tension of said threads, is rendered invariable, without the employment of any device to take up or let out the threads.

The speed of operation of the braiding machines of the prior art being materially limited by the necessary employment of thread take up devices, movable in consonance with each transposition of the threads; my improvements above described constitute an important advance in the art, in that such take up devices are dispensed with, and a machine provided costing less to manufacture and capable of operation at more than double the speed of the ordinary machines employing such devices.

For simplicity of illustration, I have shown a machine comprising but four bobbins in each series; it is to be understood, however, that my improvements may be embodied in a machine comprising any desired number of bobbins. Moreover, although I have shown the bobbins 10, of the upper series, of short length and large diameter, disposed with their axes parallel with the common axis of rotation of the drum 5, and carrier frame 16; it is obvious that said bobbins of the upper series may be made of greater length and less diameter and mounted upon the carriers with their axes radially disposed with respect to the axis of rotation of the carrier frame, as is usual in many machines of the prior art.

I do not desire to limit myself to the particular construction and arrangement of the machine which I have shown, as it is obvious that various modifications may be made therein without departing from the essential features of my invention.

I claim:

1. In a braiding machine, the combination with a bobbin drum; of a carrier frame; means to rotate said drum and frame simultaneously in opposite directions; a thread

guide arranged to conduct the thread from the bobbins on said drum, alternately over and below the thread from the bobbins progressed by said frame, to the braiding point, and comprising a curved needle with its ends off-set so as to be out of alinement; a radially arranged hollow shaft, journaled in said drum and carrying said needles; and, means to oscillate said hollow shaft as said drum rotates, substantially as set forth.

2. In a braiding machine, the combination with a rotatable drum carrying a plurality of bobbins; of a series of independent carriers concentrically supported by said drum and each carrying a bobbin; means to rotate said drum in one direction and said carriers in the opposite direction; means to guide the threads from the bobbins on the independent carriers, to the common axis of rotation of the drum and of said carriers; and means to guide the threads from the bobbins on the drum to said axis, alternately above and below the threads from the bobbins on the independent carriers, said means comprising a series of radially arranged hollow shafts journaled in said drum; a thread guide secured in each of said hollow shafts comprising a grooved needle; means to automatically oscillate said hollow shafts as the drum rotates, said means comprising a series of radial countershafts journaled in said drum; means to continuously rotate said countershafts while the drum rotates; an eccentric on the outer end of each of said countershafts; an arm secured on each of said hollow shafts; and, links connecting said eccentrics and arms, substantially as set forth.

3. In a braiding machine, the combination with a stationary frame; of a tubular bearing upon said frame; a bobbin drum mounted for rotation in said bearing; a carrier frame mounted for rotation within said drum; bevel gears respectively fixed upon said bobbin drum and carrier frame; a driving shaft; a bevel gear upon said driving shaft engaged with the bevel gears upon said drum and frame; a stationary circular rack, in concentric relation with said drum and frame; a series of radial shafts mounted for rotation in said drum; respective bevel gears upon the inner extremities of said shafts, engaged with said stationary circular rack; eccentrics, respectively fixed upon the outer extremities of said radial shafts; needles mounted to oscillate upon radial axes in said drum; means connecting said eccentrics with said needles, arranged to oscillate the latter; a series of bobbins on said drum; a series of bobbin carriers arranged to be progressed by said carrier frame; a series of bobbins, respectively mounted on said carriers; pairs of independently operative driving pins, respectively

connecting each of said carriers with said frame; said pins being mounted for reciprocation in a direction parallel with the axis of rotation of the bobbin carrier frame; and, means to alternately engage and disengage said pins with respect to said carriers, in predetermined sequence with respect to the relative progression of said drum and frame, substantially as set forth.

4. In a braiding machine, the combination with a bobbin drum; of a carrier frame; means to rotate said drum and frame concentrically in relatively opposite directions; a series of bobbins mounted upon said drum; a series of bobbin carriers arranged to be progressed by said frame; a series of bobbins respectively mounted on said carriers; means to guide the thread from the bobbins on the carriers to the braiding point; means to guide the thread from the bobbins on the drum to the braiding point, alternately above and below the thread from the bobbins on the carriers, said means comprising a series of radially arranged hollow shafts journaled in said drum; a thread guide secured in each of said shafts and comprising a grooved needle having a portion offset from its shaft; means to automatically oscillate said hollow shafts as the drum rotates, said means comprising a series of radial countershafts journaled in said drum; means to continuously rotate said countershafts while the drum rotates; an eccentric on the outer end of each of said countershafts; an arm secured to each of said hollow shafts; and, links connecting said eccentrics and arms, substantially as set forth.

5. In a braiding machine, the combination with the rotatable annular body, sets of bobbins carried thereby and means for revolving said sets in different directions, of thread carriers pivotally mounted on said body, a continuously rotating cam for each thread carrier to actuate the latter and carried by said body, and means to rotate the cams, substantially as set forth.

6. In a braiding machine, the combination with the rotatable annular body, sets of bobbins carried thereby, and means for revolving said sets in different directions, of thread carriers pivotally mounted on said body, a continuously rotating cam for each thread carrier to actuate the latter and means for rotating the cams, said means being driven by the means for revolving the bobbin sets, substantially as set forth.

In testimony whereof, I have hereunto signed my name, at Philadelphia, Pennsylvania, this tenth day of May, 1901.

SAMUEL A. NEIDICH.
